(57) **CLAIM**

The ornamental design for a cap, as shown and described.

DESCRIPTION

FIG. 1 is a perspective view of the cap;

FIG. 2 is a top view of the cap;

FIG. 3 is a bottom view of the cap;

FIG. 4 is a front view of the cap;

FIG. 5 is a back view of the cap;

FIG. 6 is a first side view of the cap; and,

FIG. 7 is a second side view of the cap.

The broken line portion of the drawing of FIG. 3 is included to show unclaimed subject matter only for the purpose of illustrating environment and forms no part of the claimed design.

This design application refers to a cap, for use in industrial containers, which will be better defined and claimed by the accompanying figures.

1 Claim, 3 Drawing Sheets
